CLAIM

The ornamental design for a vehicle glove box organizer, as shown and described.

DESCRIPTION

FIG. 1 is a front elevation view of a vehicle glove box organizer, showing my new design;

FIG. 2 is a left elevation view of the vehicle glove box organizer illustrated in FIG. 1.

FIG. 3 is a right elevation view of the vehicle glove box organizer illustrated in FIG. 1;

FIG. 4 is a rear elevation view of the vehicle glove box organizer illustrated in FIG. 1;

FIG. 5 is a bottom plan view of the vehicle glove box organizer illustrated in FIG. 1;

FIG. 6 is a top plan view of the vehicle glove box organizer illustrated in FIG. 1; and,

FIG. 7 is a left perspective elevational view of the vehicle glove box organizer illustrated in FIG. 1, depicted in a closed position.

The broken line showing environment is for illustrative purposes only and forms no part of the claimed design.
